UNITED STATES PATENT OFFICE.

DANIEL A. CROCKER, OF ALMOND, WISCONSIN.

SLEIGH.

1,127,194.

Specification of Letters Patent.

Patented Feb. 2, 1915.

Application filed June 4, 1914. Serial No. 842,971.

To all whom it may concern:

Be it known that I, DANIEL A. CROCKER, a citizen of the United States, residing at Almond, in the county of Portage and State of Wisconsin, have invented certain new and useful Improvements in Sleighs; and I do declare the following to be a full, clear, and exact description of the invention, such as will enable others skilled in the art to which it appertains to make and use the same.

10 This invention relates to improvements in sleighs and more especially to beams and runner stands therefor.

15 The object of the invention thereof is to provide a runner stand and angle steel truss bar which may be used in the construction of new sleighs or sleds or applied to any sleigh already in use.

20 With this and other objects in view, the invention consists of certain novel features of construction, and the combination and arrangement of parts as will be hereinafter described and claimed.

25 In the accompanying drawings: Figure 1 represents a side view of a portion of a sleigh equipped with this invention: Fig. 2 is a bottom plan view thereof: Fig. 3 is a transverse section through the sleigh taken longitudinally through the beam: Fig. 4 is a 30 horizontal section through the beam: Fig. 5 is a transverse vertical section through the beam: Fig. 6 is a detail perspective view of one of the braces.

35 In the embodiment illustrated angle iron runners 1 are shown connected at their front ends by a cross rod or bar 2 and having stands 3 mounted thereon and shown in the form of plates inverted U-shaped in cross section with their free ends secured to the 40 opposite flanges of the runners. Bowed brace bars 4 extend through these stands 3 between the side members thereof longitudinally of the runners and are each secured at their ends to the bottom or cross bar of 45 a runner at points spaced from said stand.

45 As shown these brace bars 4 are made wider than the space between the side members of the stand and have their edges cut out to adapt them to pass between the side 50 members of the stand and thereby forming stops at the opposite edges of the stand to prevent its edgewise movement.

55 The beam 5 comprises a shell-like casing composed of an angle iron 6 substantially 110 inverted U-shaped in cross section with suitable closures 7 at its opposite ends, said

closures being here shown in the form of U-shaped clips or yokes which are secured to the side flanges of the rim, and have longitudinally extending sleeves 13 forming bearings for a purpose to be described. 60

A U-shaped bracing clip 8 is mounted midway the ends of the shell 6 between the side flanges thereof and is secured thereto by any suitable means, a U-shaped bolt 9 65 being here shown extending transversely through the beam and the ends of the clip 8 with the terminals of said bolt bent outwardly in opposite directions to securely hold it in engagement with the beam casing. 70 A king bolt 10 extends through the cross bar of the casing between the arms of the bolt 9 and through the cross bar of the clip 8. This bolt also extends through a rod 11 75 midway the length of said rod. This rod 11 extends longitudinally of the casing 6 and the ends thereof are extended through the end sleeves of said casing and transversely through the runner stands, after which they are upset against washers 12. The ends of 80 this rod extend through the stands near their upper ends thereby positioning the rod in outwardly bowed form, the central portion thereof being preferably flattened to adapt it to rest firmly against the bracing clip 8 85 and is apertured to receive the king bolt.

Arranged on opposite sides of the rod 11 are two truss rods 14 and 15 which bear intermediately of their ends against the lower face of the brace clip 8 and the ends thereof 90 extend through the top or cross bar of the casing 6 near the ends of said casing and may be secured in place by any suitable means, said ends being here shown bent slightly to hold them in operative position. 95 By so constructing this beam the angle casing thereof may be made of very light steel as it is supported by the truss rods 14 and 15.

While one beam only has been described it will be obvious that any desired number 100 may be employed according to the size of the sleigh and the number of bobs used.

The rod 11 is pivotally mounted in the stands 3 whereby the beam is adapted to turn between said stands. 105

I claim as my invention:

1. The combination with a pair of spaced runners, and a transverse beam connecting the same and having a central opening, of a plate secured to said beam and located beneath the center thereof, said plate having an opening alining with the opening in the

beam, a transverse truss rod beneath the beam and having its opposite ends held against movement in respect thereto, the center of said rod underlying said plate and 5 having an opening alining with the other openings and an upright king pin positioned in the alined openings.

2. The combination with a pair of spaced runners, a stand rising from each runner, 10 and a bearing on each stand, of a channel iron beam having its ends located adjacent said bearings, flat upright plates abutting the ends of said beam and having flanges secured thereto, stub shafts projecting longitudinally outward from said plates into 15 the bearings, and stops on said stub shafts.

3. In a sled of the class described, a pair of spaced parallel runners, a pair of arched brace bars rising therefrom and having their

arms secured thereto at longitudinally 20 spaced points, the crowns of said arched bars having longitudinally spaced stops, and a pair of arched plates straddling said crowns of the brace bars between the stops thereon, the free ends of said arched plates being 25 spaced transversely and connected to the runners, and the crowns thereof contacting with the crowns of the arched brace bars, in combination with means connecting the two arched plates to space the two runners and 30 to support a load.

In testimony whereof I have hereunto set my hand in presence of two subscribing witnesses.

DANIEL A. CROCKER.
